Attorney.

UNITED STATES PATENT OFFICE.

ERNST F. DECKER, OF ALBANY, NEW YORK.

DOOR-CHECK.

SPECIFICATION forming part of Letters Patent No. 308,880, dated December 9, 1884.

Application filed October 25, 1883. (Model.)

To all whom it may concern:

Be it known that I, ERNST F. DECKER, of the city and county of Albany, in the State of New York, have invented certain new and useful Improvements in Door-Fasteners, of which the following is a specification.

My invention relates to improvements in automatic devices for retaining doors in an open position; and the object of my improvement is to provide, for the purpose above named, a simple and effective device, which, being provided with a guard attachment, may be instantly thrown out of use. I attain this object by means of the mechanism illustrated in the accompanying drawings, which form part of this specification, and in which—

Figure 1 is a side elevation of my device as applied to a door; Fig. 2, an enlarged side elevation of the catch and staple detached; 20 Fig. 3, a plan view of the same, and Fig. 4 a side elevation of the catch with the guard attachment in position for preventing the staple from engaging with the catch.

As represented in the drawings, A is the catch-lever, pivoted at a to a bracket, B, which is designed to be secured upon the floor behind the door D, where it will retain the latter in an opened position. Said catch-lever is provided on its outer end with a pendent hook, a', whose outer face is inclined inwardly, as shown in Fig. 2. Above said hook a guard, a², is pivoted to the catch-lever, so as to lie upon the upper side thereof, as shown in Fig. 2, or, when occasion requires, to be thrown down in front of the hook a', as shown in Fig. 4. The opposite end of the catch-lever A is provided with a tread-plate, a³, which may extend rearward, as shown in the drawings, or, when required to economize space, it may be bent upward, either vertically or at an angle. A spring, a⁴, attached to the catch-lever A, is arranged to bear upon the bracket B behind the pivot a, so as to press the point of the hook a' in contact with the seat of the bracket.

The bracket B has a seat, b, whose outer end inclines inwardly, as shown in Fig. 2, and it is also provided with ears b', to which the catch-lever A is pivoted.

The staple C is intended to be secured to the back of the door D, and is provided with a cross-bar, c, which engages behind the hook a' of the catch-lever, as indicated by the dotted lines in Fig. 1, and secures the door in an opened position.

The operation of my device is as follows: The bracket B is secured to the floor and the staple C to the door, in the relative positions shown in Fig. 1; then, while the guard a² is raised, as shown in Fig. 2, when the door 60 is thrown wide open the cross-bar c of the staple will strike against the inclined face of the hook a' and cause that end of the catch-lever A to rise and admit the cross-bar c into the space behind the hook a'. As soon as this 65 is accomplished the spring a⁴ restores the catch-lever A to its normal position, so as to lock the cross-bar c behind the hook a' and effect the retention of the door D in its 70 opened position. The releasement of the door is effected by simply pressing upon the tread-plate a³, whereby the hook a' is raised, to permit the cross-bar c to pass out from beneath the catch-lever A. When the guard a² is thrown down, as shown in Fig. 4, the cross-bar c is prevented from passing under the 75 catch-lever A, and the door is left free to close at will.

When preferred, the spring a⁴ may be dispensed with by placing a preponderance of 80 weight at the hook end of the catch-lever; and when the fastener is applied to use on doors which are seldom to be closed the guard a² may be dispensed with.

I claim as my invention—
85
In a door-fastener, the combination, with a catch-lever, A, pivoted to a bracket, B, and having a hook, a', formed thereon, and a guard, a², pivoted thereto, as herein set forth, of a staple, C, adapted to engage with the hook a', in the manner and for the purpose herein specified.

ERNST F. DECKER.
